US0D1056643S

(12) **United States Design Patent** (10) **Patent No.:** **US D1,056,643 S**
(45) **Date of Patent:** **** Jan. 7, 2025**

(54) **FOOD CUTTER**

(71) Applicant: **Zhejiang Fullstar Houseware Co., Ltd.**, Taizhou (CN)

(72) Inventor: **Congqiang Lu**, Taizhou (CN)

(**) Term: **15 Years**

(21) Appl. No.: **35/518,327**

(22) Filed: **May 18, 2023**

(80) **Hague Agreement Data**

Int. Filing Date: **May 18, 2023**

Int. Reg. No.: **DM/231186**

Int. Reg. Date: **May 18, 2023**

Int. Reg. Pub. Date: **Sep. 15, 2023**

(30) **Foreign Application Priority Data**

Mar. 15, 2023 (CN) 202330120727.3

(51) **LOC (15) Cl.** **07-04**

(52) **U.S. Cl.**

USPC **D7/673**

(58) **Field of Classification Search**

USPC D7/372, 381, 383, 384, 412, 672, 673, D7/674, 675, 676, 677, 678, 679, 693

CPC A47J 17/02; A47J 43/25; A47J 43/255; B26D 3/283
